UNITED STATES PATENT OFFICE.

AXEL W. BJORKMAN, OF BROOKLYN, NEW YORK, ASSIGNOR TO OTIS ELEVATOR COMPANY, OF NEW YORK, N. Y., A CORPORATION OF NEW JERSEY.

COIL-WINDING DEVICE.

Application filed November 29, 1926. Serial No. 151,494.

This invention relates to coil-winding devices and particularly to devices for winding coils to be used for armatures of dynamo-electric machines.

5 A feature of the invention is to provide a device of the above character that is of simple construction and easily operated.

Another feature of the invention resides in the provision of a device of the above 10 character that requires but little manual adjustment and reduces to a minimum the time required to wind a coil.

A third feature of the invention is to provide a coil-winding device from which 15 the coil may be quickly removed without the possibility of injury resulting to the coil or to its insulation.

Other features and advantages will become apparent from the specification, taken 20 in connection with the accompanying drawings wherein the invention is embodied in concrete form.

In the drawings:—

25 Figure 1 is a view in elevation with parts broken away of the coil winding device;

Figure 2 is a sectional view taken along the line 2—2 of Figure 1;

Figure 3 is a view in part section taken along the line 3—3 of Figure 1;

30 Figure 4 is a view in part section taken along the line 4—4 of Figure 3;

Figure 5 is a sectional view taken along the line 5—5 of Figure 1;

Figure 6 is a view in part section taken 35 along the line 6—6 of Figure 1;

Figure 7 is a view in part section taken along the line 7—7 of Figure 1;

Figure 8 is a side view of Figure 1 with parts broken away;

40 Figure 9 is a schematic illustration of the winding device in operation;

Figure 10 is a view similar to Figure 9 and illustrates the employment of a different type of wire clamp;

45 Figure 11 is a view in part section taken along the line 11—11 of Figure 10; and

Figure 12 is a sectional view taken along the line 12—12 of Figure 11.

Reference may first be had to Figures 1 50 and 8 illustrating the device as a whole, wherein, according to the preferred arrangement a driving means or motor 1 having a driving shaft 2 is secured by screws 3 to a base plate 4. A sprocket wheel 5 is keyed 55 on the driving shaft 2 and is retained

thereon by a set-screw 6. A sprocket chain 7 extends around the sprocket wheel 5 and around a sprocket wheel 8 having a hub 9 rotatably mounted on a worm shaft 10. The hub 9 of sprocket wheel 8 has a bushing 11 surrounding the shaft 10. A collar 12 is secured on the worm shaft adjacent one side of the hub 9. A stationary bearing bracket 20 is positioned adjacent the other side of the hub 9. Collar 12 and bracket 60 20 prevent the sprocket wheel 8 from sliding along the worm shaft 10. Bearing bracket 20 is secured to a gear housing 22 by screws 25. This bearing bracket has a bushing 21 surrounding and supporting the shaft 10. 70

The worm shaft 10 extends into the gear housing 22. Gear housing 22 has two removable bearings 23 and 24 that support the worm shaft. Bearing 23 is secured to the gear housing by screws 26. This bearing is provided with a stuffing-box 27 having a packing-nut 28 for the purpose of retaining lubricant within the gear housing. Bearing 24 is formed with a thrust bearing recess 30. A ball thrust bearing 31 is positioned within the recess 30 and is mounted on a reduced end portion of the worm shaft. A retaining nut 29 is threaded on the end of shaft 10 adjacent the bearing 31. A cap 32 covers the outer end of bearing 24. Cap 75 32 and bearing 24 are secured to the gear housing 22 by screws 33 extending through these members and threaded into the gear housing. The gear housing 22 is mounted on a supporting frame 34 and is secured to this frame by screws 35. Frame 34 consists of two pedestals 36 and 37 rigidly connected by cross-bars 38 and 40 bolted to the pedestals. Bolts 41 secure the base plate 4 to the frame 34. 90

The sprocket wheel 8 is formed at its periphery with a laterally extending flange 14. This flange has its inner surface tapered and constitutes a jaw of a cone clutch 15. The other jaw 16 of cone clutch 15 has its hub 17 mounted on the worm shaft 10. A key 18 is secured to shaft 10 and extends through a keyway in the hub 17 of jaw 16. Hub 17 100 may slide along the worm shaft 10 but is prevented by key 18 from turning with respect to this shaft. The periphery of hub 17 is provided with an annular groove 44. A clutch lever 45 having the form of a bell crank is pivoted on a pin 46 extending through the bracket 20. The pin 46 is pro- 105 110

vided with a head at one end and a nut 47 on the other end for retaining the pin in the bracket 20. Bracket 20 is recessed at 48 to accommodate the clutch lever 45. 5 The upper portion of clutch lever 45 extends around one side of the hub 17 of the jaw 16 and carries a bolt 50 that extends through an aperture in the clutch lever. A roller 51 (see Figure 2) is rotatably mounted on 10 the bolt 50 and is positioned within the groove 44 of the hub 17. A roller support 53 is secured by bolts 56 to the upper portion of the clutch lever 45. Roller support 53 extends around the other side of the hub 17 15 of the jaw 16 and carries a bolt 54 that extends through an aperture in the roller support. A roller 55 is rotatably mounted on the bolt 54 and is positioned within groove 44 of the hub 17.

20 Referring again to Figures 1 and 8, one end of a vertically arranged link 59 is pivotally connected to lever 45 by a bolt 57. The other end of link 59 is pivotally connected by a bolt 58 to a lever 60. Lever 25 60 is keyed to a rock shaft 61 that has bearings in the pedestals 36 and 37 of the frame 34. Collars 62 are secured to the rock shaft 61 by set screws 63 and are positioned adjacent the frame 34 for the purpose 30 of retaining this shaft within its bearings in the frame 34. The rock shaft extends outwardly from each side of the frame 34 and is supported in two pedestals. Only 35 one of these pedestals is illustrated and is designated 64. One end of this shaft is keyed to a foot lever 65 and the other end is likewise keyed to a foot lever, not shown.

40 Clutch lever 45 is provided at one end with an aperture 67. A tension spring 68 has one end extending through the aperture 67 and its other end wrapped around a bolt 69. Bolt 69 extends through apertures in the pedestals 36 and 37 of the frame 34.

45 The worm 70 of the worm shaft 10 meshes with a worm wheel 71. The hub 79 of wheel 71 is keyed to the central enlarged portion 72 of the worm wheel shaft 73. Shaft 73 is supported in bearing bushings 75 and 76 mounted in the gear housing 22. Shaft 73 has reduced end portions 77 and 78 extending outwardly from the gear housing. End portion 77 is threaded for a portion of its length with a right hand thread. End portion 78 is threaded for a portion of its length with a left hand thread. A winding bar holder 80 is threaded upon the end portion 78. Winding bar holder 80 is formed with a circular aperture 81 extending at right angles to the worm wheel shaft 73. A winding bar 74 extends through the aperture 81 and may slide longitudinally through this aperture. Set screws 82 and 83 are threaded through the bar holder 80 and engage suitable recesses in the winding bar 74 for retaining this bar in the bar holder.

A key 84 is secured by screws 85 to the winding bar 74 and extends the full length of this bar. Key 84 extends through a keyway 86 provided in the aperture 81 of the bar holder. The rectangular end face 87 of 70 the bar holder 80 is provided with two diagonally arranged threaded recesses 88 and 90.

The base 94 (see Figures 3 and 4) of a wire clamp 91 is secured to the face 87 by 75 screws extending through apertures in the clamp base 94 and threaded into the recesses 88 and 90. Diagonally arranged dowels 92 and 93 are fixed in apertures in the clamp base 94 and extend into recesses provided 80 in the bar holder 80. The body portion 95 of the wire clamp 91 (see Figure 3) is formed with an aperture 96 of rectangular cross-section. This aperture extends at right angles to the clamp base 94 and acts as a 85 guide for a clamp bar 97. Clamp bar 97 carries a guide pin 98. Guide pin 98 is secured in a recess in one end of the clamp bar 97 and extends through a coil compression spring 100 and through an aperture in 90 a spring retaining plate 101. Retaining plate 101 is positioned within a recess in the clamp base 94 and is secured within this recess by two screws 102. The bar holder 80 is provided with an aperture 103 in 95 alignment with the guide pin 98. The clamp bar 97 is formed with an aperture 104. A side 105 of the aperture 104 is tapered and engages the inclined face 106 of a wedge 107 that extends through the 100 aperture 104. The body portion 95 of the wire clamp 91 has an aperture 108 extending at right angles to the aperture 96. The wedge 107 is positioned within the aperture 108 and rests against the walls of this aperture. The narrow end of the wedge 107 carries a guide pin 110 similar to the guide pin 98. Guide pin 110 extends through a coil compression spring 111 and through an aperture 112 in a spring retaining plate 113. 110 Spring retaining plate 113 is secured on the body portion 95 of wire clamp 91 by dowels 114 and screws 115. A plate 116 is secured on the body portion 95 by dowels 117 and screws 118. A clamp screw 120 is threaded 115 through an aperture in the plate 116 and engages the wedge 107.

A pivotal stud 119 has a reduced end 121 that is threaded through the clamp bar 97. Stud 119 has a jaw member 122 pivoted 120 thereon. Jaw member 122 has a gripping portion 124 that extends from a hub portion 123. A part of hub portion 123 is positioned within a cylindrical recess provided in the clamp bar. The gripping portion 124 has a 125 curved serrated gripping face 125. The curve of the gripping face 125 is eccentric with respect to the pivotal stud 119. A leaf spring 126 is secured to an anchor pin 127 extending from the clamp bar 97. One side 130

- of this spring bears against a pin 128 extending from the clamp bar and the other side of this spring bears against a side 130 of the gripping portion 124 of the jaw member.
- 5 The opposite side 131 of the gripping portion 124 bears against a stop shoulder 132 formed on the clamp bar 97.
- A jaw member 133 is arranged to cooperate with jaw member 122. Jaw member 133 has a serrated edge 134 and is secured to the body portion 95 of the clamp 91 by screws 135 extending through apertures in the jaw member and threaded into the body portion of the clamp.
- 10 Winding bar 74 and key 84 extend through an aperture 137 in a winding block holder 136. Winding block holder 136 may slide along the winding bar 74 but is prevented by key 84 from turning with respect to this bar. As illustrated in Figures 5 and 6 winding block holder 136 is formed with a threaded recess 138 extending at right angles to the aperture 137. A cylindrical winding block 140 is threaded into the recess 138.
- 15 The winding block may be adjusted within the recess 138 by turning this block with respect to the block holder 136. The winding block is secured in its adjusted position within the block holder 136 by means of a set screw 142. This set screw engages one or the other of two diametrically arranged slots 143 and 144 provided in the winding block and prevents the turning of the winding block within the holder 136. The winding block has a tongue 145 extending outwardly therefrom. This tongue comprises a winding portion 146 and a reduced end portion. The reduced end portion is cut away midway of its length so as to form a central cylindrical part 147 joining two non-circular end parts 148 and 150.
- 20 A guide washer 151 has an aperture 152 that is made to fit the reduced end portion of the tongue 145. This washer is positioned on end part 148 of the reduced end portion and has a cylindrical recess 156. The disk shaped body 154 of a lock nut 155 is positioned within the recess 156. This body 154 of the lock nut 155 is retained within recess 156 by two semi-annular retaining plates 157 and 158. Retaining plates 157 and 158 are secured by screws 160 to the guide washer and extend over the body 154 of the lock nut. The body 154 of the lock nut has a centrally positioned aperture 161 that is made to fit the reduced end portion of the tongue 145. Body 154 of lock nut 155 has an annular flange 162 extending outwardly therefrom. This flange has an enlarged knurled portion 163 for the purpose of permitting manual adjustment of the lock nut on the reduced end portion of the tongue 145.
- 25 The guide washer 151 and the lock nut 155 form a unit 164 that may be placed on or re-
- 30 moved from the reduced end portion of the tongue 145. To place this unit 164 on the reduced end portion of the tongue the apertures 161 and 152 in the lock nut and guide washer respectively are made to align with one another. This is accomplished by turning the body 154 of the lock nut within the recess 156 of the guide washer. The unit is then slipped over the reduced end portion of the tongue so that the guide washer rests on end part 148 and the lock nut body 154 is opposite the cylindrical part 147. The lock nut is then turned causing the disk shaped body 154 to turn about the cylindrical part 147. The wall of the body 154 adjacent the aperture 161 enters the cut away part of the reduced end portion of the tongue 145 thus locking the unit 164 on the winding block 140. To remove the unit from the winding block the lock nut is turned so that its aperture 161 is again in alignment with aperture 152 whereupon the nut may be slipped off of the reduced end portion of the tongue 145.
- 35 The winding block holder 136 is formed with a threaded recess 165. An eye-bolt 166 is threaded into the recess 165. The eye-bolt 166 extends through a compression spring 169 and through an aperture 167 in a clamp 168. The compression spring 169 bears at one end against the winding block holder 136 and at the other end against the clamp 168. Clamp 168 has legs 176 and 177 that extend around the winding bar 74. A screw 178 extending through an aperture in leg 176 and threaded into leg 177 causes these legs to bind upon the bar 74, thus securing the clamp on this bar. A releasing lever 172 has a bifurcated end portion 171. A pivotal pin 170 is carried by the bifurcated end portion 171. Pin 170 extends through the eye or aperture 175 in the head of eye-bolt 166. The bifurcated end portion 171 has the form of a cam and is arranged to coact with the clamp 168. The cam surface 110 of the bifurcated end portion 171 is flat at the end 173 and side 174, while this surface is curved between these parts. End 173 is spaced further from the pin 170 and eye 175 than is side 174. The releasing lever 172 may be turned about the head of the eye-bolt 166 causing the cam surface of the end portion 171 to slide over the adjacent surface of the clamp 168. Compression spring 169 urges winding block holder 136 away 115 from the clamp 168 and causes the cam surface of the end portion 171 to bear against the clamp 168. When the end 173 engages the clamp 168 the winding block holder is nearer this clamp than when the side 174 120 engages this clamp.
- 40 Winding bar 74 and key 84 extend through an aperture 179 in a winding block holder 189. Winding block holder 189 is similar to winding block holder 136 with the exception 125

tion that holder 189 is fixed on the winding bar whereas holder 136 may slide along this bar. Holder 189 is split at 180 forming clamping legs 181 and 182. A screw 183 extending through an aperture in leg 181 and threaded into leg 182 causes these legs to bind upon the bar 74, thus securing the winding block holder on this bar. Holder 189 carries a winding block 184 (see Figure 7) of the same construction as winding block 140. The winding portion of the tongue 187 of this winding block is designated 185. A removable unit 186 of the same construction as the unit 164 is positioned on the reduced end portion of the tongue 187.

The end portion 77 of the worm wheel shaft 73 is adapted to support a bar holder and its associated apparatus in the same manner that the end portion 78 of this shaft supports bar holder 80 and its associated apparatus.

The operation of the coil winding device is illustrated in Figure 9. The wire 188 to be wound is led from the reel 190 through a tensioning apparatus 191 to the winding device. The tensioning apparatus 191 grips the wire with a force sufficient to cause the proper tension to be applied to the wire as it is wound into a coil by the winding device.

To carry out the winding operation the operator leads the wire 188 over the winding portion 185 of the winding block 184 carried by the holder 189. He places the end of the wire 188 on the clamp bar 97 between the jaw members 122 and 133 of the wire clamp 91. Should the space between these jaw members be insufficient to admit the insertion of the wire 188, the clamp screw 120 is turned so that this screw moves outwardly of the body portion 95 of the wire clamp and away from the wedge 107. As the clamp screw 120 starts to move outwardly the compression spring 111 causes the wedge 107 to move along with the screw 120. As the wedge 107 commences to move along with the screw 120, the compression spring 100, acting on the clamp bar 97, causes the tapered side 105 of this bar to slide along the inclined face 106 of the wedge 107. As side 105 slides along the face 106 the clamp bar moves outwardly, causing the jaw member 122 to move away from the jaw member 133 so that the wire may be inserted.

With the wire inserted between the jaw members 122 and 133 the clamp screw 120 is turned in the reverse direction to that described above, causing the wedge 107 to compress the spring 111 and to move the clamp bar inwardly against the pressure of the spring 100. This inward movement of the clamp bar causes the jaw members 122 and 133 to securely grip the wire between them.

The end 173 of the releasing lever 172 is placed in engagement with the clamp 168 and

the wire is then ready to be wound. To wind the wire the operator presses down on the foot lever 65 causing the turning of rock shaft 61. As rock shaft 61 turns it swings lever 60 causing link 59 to move upwardly. The upward movement of link 59 is transmitted by bolt 57 to the clutch lever 45 by overcoming the tension of spring 68 and causes this lever to turn about its pivotal pin 46. As the clutch lever commences to turn, the rollers 51 and 55 carried by this lever engage the side of groove 44 in the hub 17 of the clutch jaw 16. Continued movement of the clutch lever causes rollers 51 and 55 to move the clutch jaw 16 into engagement with the tapered surface of the flange 14 formed integral with sprocket wheel 8.

The motion of the motor 1 is now transmitted through sprocket wheel 5, sprocket chain 7, sprocket wheel 8, clutch 15, key 18, worm shaft 10, worm wheel 71, and worm wheel shaft 73 to the winding bar holder 80, causing the winding bar holder to turn the winding bar 74 in a clockwise direction as viewed in Figures 1 and 9.

As the winding bar 74 starts to turn and the tension in the wire 188 increases owing to the gripping action of the tensioning apparatus 191, there may be a tendency for the wire to slip out from between the jaw members 122 and 133. Should the wire start to slip as a result of this tendency, its motion is arrested by the action of the gripping face 125 of the jaw member 122. Since the contour of this face is eccentric to that of the pivotal stud 119 about which it turns, any slipping movement of the wire causes the jaw member 122 to turn about the pivotal stud 119 in a direction to cause a lessening of the distance between the gripping faces of the jaw members 122 and 133. The wire is thus securely gripped by the action of the jaw members and is prevented from slipping.

As the winding bar continues to turn, the movement of the winding block 184 causes the wire to be bent around the winding portion 185 of this block. Continued movement of the winding bar causes the wire to be bent around the winding portion 146 of the winding block 140 as illustrated in Figure 9. Successive revolutions of the winding bar causes the wire to be wrapped in successive layers upon the winding portions 185 and 146. The winding block holders and the guide washers guide the wire so that successive layers are superimposed upon the preceding layers.

When a coil of the desired number of layers has been formed, the operation of the winding device is stopped by releasing the foot lever 65. Upon the release of this lever, the tension spring 68 causes the clutch lever 45 to be swung about its pivotal pin 46 in the direction to effect the disengagement of

the jaws of the clutch 15. The movement of the motor 1 is no longer transmitted to the winding bar and this bar comes to rest. The wire leading to the newly formed coil may now be cut. The end of the wire that is held by the wire clamp may be withdrawn from this clamp by moving the wire away from the clamp bar in a direction parallel to the pivotal axis of the jaw member 122. This movement of the wire is not resisted by the serrated faces of the jaw members since it takes place in a direction that is parallel to the serrations and not across them.

By removing the units 164 and 186 comprising the guide washers and lock nuts from their winding blocks in the manner already described, the coil may be removed from the winding device. Owing to the tension exerted upon the wire during the winding operation, the completed coil grips the winding portions 185 and 146 with considerable force. To remove the coil without first relieving it of this tension would result in injury to the coil. The purpose of the releasing lever 172 is to relieve the tension in the coil and thereby eliminate the gripping of the winding portions by the coil. By turning this lever so that the side 174 engages the clamp 168, the spring 169 causes the winding block holder 136 to move away from the clamp 168 and in the direction of the winding block holder 189. The winding portion 146 moves along with holder 136 thus shortening the distance between the winding portions 185 and 146. The coil may now be removed from the winding portions.

In the event that two winding bars are carried by the worm wheel shaft, the winding device may be used to wind two coils simultaneously.

A different type of wire clamp may be used in lieu of wire clamp 91. Figures 10, 11 and 12 illustrate the use of such a wire clamp. In these figures a wire clamp 192 is mounted on the winding bar. Wire clamp 192 comprises a bracket 193 having legs 194 and 195 extending around the bar 74. A screw 196 extending through an aperture in leg 194 and threaded into leg 195 causes these legs to bind upon the bar 74; thus securing the clamp to this bar. Bracket 193 is formed with a bearing aperture 199. The body portion 197 of the wire clamp has a pivotal stud 198 extending through the bearing aperture 199. A screw 200 and washer 201 retain the stud 198 within the bearing aperture 199. A clamp screw 202 is threaded through the body portion 197 and has a reduced end portion 203 extending into a recess in a jaw 204. The reduced end portion 203 of the clamp screw is formed with an annular groove 206. A pin 207 extends through an aperture in the jaw 204 and into the groove 206, thereby retaining the jaw 204 on the clamp screw 202.

Jaw 204 is formed with an inclined guideway 208 of T cross-section. A wedge shaped jaw member 210 of T cross-section is positioned within the guideway 208. A guide pin 211 has one end fixed within a recess in the jaw member 210 and extends through a coil compression spring 212. The spring 212 bears at one end against the jaw member 210 and at the other end against a bracket 213 carried by the jaw 204. The bracket 213 has an aperture 214 in axial alignment with the pin 211 in order to permit this pin to extend through the bracket 213. The spring 212 urges the jaw member 210 against a stop plate 215 secured by screws 216 to the jaw 204. A stop plate 222 is secured by screws 223 to the body portion 197 and extends in the path of jaw member 210.

The gripping face 217 of the jaw member 210 is serrated and is arranged to cooperate with the serrated gripping face 218 of a jaw member 220. Jaw member 220 is secured by screws 221 to the body portion 197 of the wire clamp.

In operation the end of the wire 224 to be wound is led from reel 225 through tensioning apparatus 226 to the wire clamp 192. The end of the wire is inserted between the jaw members 210 and 220 and the clamp screw 202 is adjusted so as to cause the gripping faces of these members to grip the wire between them.

Should the wire commence to slip as the coil is wound, the jaw member 210 moves with the wire and at the same time slides along the inclined guideway 208. This movement of the jaw member 210 causes its gripping face 217 to move in the direction of the gripping face 218 until the clamping action of these gripping faces upon the wire causes the slipping of the wire to cease.

When the coil has been wound it may be withdrawn from the winding blocks after the removal of the guide washers and the operation of the releasing lever as above described.

It is to be noted that, by adjusting the winding blocks within the winding block holders, the winding device may be used for wires of various sizes. Also wires having cross-sections of various shapes, such as round, square or rectangular may be wound.

It is further noted that the coils as they come from the winding device are flat with their sides parallel and having a number of turns as desired. It will be understood that these coils are then properly cut and spread to the form in which they are to be used.

Owing to the automatic adjustment of the jaw members of the wire clamps to prevent the slipping of the wire while it is being wound, time is saved in the winding operation which would otherwise be consumed were manual adjustment of these members

necessary. Where a number of coils employing the same size of wire are to be wound, it is only necessary to turn the clamp screw of the wire clamp so as to cause the clamp to grip the end of the wire of the first coil to be wound. Thereafter the ends of the wire for the successive coils may be gripped by the clamp, without turning the clamp screw, by merely pushing the wire into the recess between the jaw members.

The use of the releasing lever and its associated mechanism permits the ready removal of the completed coil from the winding blocks without injuring the coil or its insulation.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

25. What is claimed is:

1. A coil-winding device comprising a winding bar, a wire clamp associated with said winding bar and arranged to grip the end of the wire to be wound, a winding block carried by said winding bar, and operating means, said operating means causing the winding bar to wind the wire upon the winding block.

2. A device for winding wire into coils comprising motive means, a winding bar, a clamp associated with the winding bar and arranged to grip the end of the wire to be wound, and a pair of winding blocks mounted on said winding bar, said winding bar being operated by the motive means to cause the wire to be wound upon the winding blocks.

3. A device for winding wire into coils comprising motive means, a winding bar, a clamp associated with the winding bar and arranged to grip the end of the wire to be wound, a pair of winding blocks mounted on said winding bar, and guide members mounted on said winding blocks and adapted to guide the wire onto said winding blocks, said winding bar being operated by the motive means to cause the wire to be wound upon the winding blocks.

4. A device for winding wire into coils comprising motive means, a winding bar, a clamp associated with the winding bar and arranged to grip the end of the wire to be wound, a pair of winding blocks mounted on said winding bar, and removable guide members mounted on said winding blocks and adapted to guide the wire onto said winding blocks, said winding bar being operated by the motive means to cause the wire to be wound upon the winding blocks, and said guide members being removable to permit

the withdrawing of the completed coil from the winding blocks.

5. A device for winding wire into coils comprising motive means, a winding bar, a clamp associated with the winding bar and arranged to grip the end of the wire to be wound, a pair of winding blocks mounted on said winding bar, removable wire guides mounted on said winding blocks, and means for locking the guides on said winding blocks, said winding bar being operated by the motive means to cause the wire to be wound upon the winding blocks, and said guide members being removable, upon the unlocking of the locking means, to permit the withdrawing of the completed coil from the winding blocks.

6. A device for winding wire into coils comprising motive means, a winding bar, a clamp associated with the winding bar and arranged to grip the end of the wire to be wound, a pair of winding blocks mounted on said winding bar, and releasing means for moving one of said winding blocks with respect to the other winding block, said winding bar being operated by the motive means to cause the wire to be wound upon the winding blocks and thereby form a coil that may be removed from the winding blocks after an operation of the releasing means.

7. A device for winding wire into coils comprising motive means, a winding bar, a clamp associated with the winding bar and arranged to grip the end of the wire to be wound, a pair of winding blocks mounted on said winding bar, a releasing lever associated with one of said winding blocks, and removable guide members mounted on said winding blocks and adapted to guide the wire onto said winding blocks, said winding bar being operated by the motive means to cause the wire to be wound upon the winding blocks and thereby form a coil that may be withdrawn from the winding blocks upon the removal of the guide members from the winding blocks and the actuation of the releasing lever.

8. A device for winding wire into coils comprising motive means, a winding bar, a clamp associated with the winding bar and arranged to grip the end of the wire to be wound, a pair of winding blocks mounted on said winding bar, a releasing lever associated with one of said winding blocks, removable guide washers mounted on said winding blocks and adapted to guide the wire onto said winding blocks, means for locking the guide washers on said winding blocks, and a releasing lever associated with one of said winding blocks, said winding bar being operated by the motive means to cause the wire to be wound upon the winding blocks and thereby form a coil that may be withdrawn from the winding blocks.

upon the removal of the guide members after the unlocking of the locking means and the actuation of the releasing lever.

9. In a coil-winding machine, a revolvable member, and a clamp attached to said revolvable member, said clamp comprising opposed jaw members for gripping the material to be wound, one of said jaw members being manually and automatically adjustable with respect to the other jaw member.

10. In a coil-winding machine, a revolvable member, and a clamp attached to said revolvable member for gripping the material to be wound, said clamp comprising a body portion, a jaw member secured to said body portion, a bar adjustably carried by said body portion, and a jaw member pivotally mounted on said bar.

11. In a coil-winding machine, a revolvable member, and a clamp attached to said revolvable member, said clamp comprising a body portion, a jaw member secured to said body portion, a bar carried by said body portion, a second jaw member pivotally mounted on said bar, a wedge cooperating with said bar, and means for moving said wedge so as to cause the bar to move and effect the gripping of the material to be wound by the jaw members.

12. In a coil-winding machine, a revolvable member, a winding block holder mounted on said revolvable member, a winding block carried by said winding block holder, said winding block comprising a winding portion and a reduced end portion,

and a removable unit mounted on the reduced end portion, said unit comprising a guide washer and a lock-nut for locking the guide washer on the reduced end portion.

13. In a coil-winding machine, a revolvable member, a clamp secured on said revolvable member, a movable winding block holder mounted on said revolvable member, a member connecting said winding block holder to said clamp, means for moving said connecting member with respect to said clamp and thereby effect movement of the winding block holder, a winding block carried by said winding block holder, said winding block comprising a winding portion and a reduced end portion, and a removable unit mounted on the reduced end portion, said unit comprising a guide washer and a lock unit for locking the guide washer on the reduced end portion.

14. In a coil-winding machine, a winding bar rotatable about a transverse axis, a pair of winding block holders mounted on said winding bar on opposite sides of said axis of rotation, means for preventing the winding block holders from turning about the longitudinal axis of the winding bar, means for locking the winding block holders in adjusted position on the winding bar, and means for permitting a limited movement of one of said winding block holders with respect to the other.

In testimony whereof, I have signed my name to this specification.

AXEL W. BJORKMAN.
